UNITED STATES PATENT OFFICE

DORA FOLEY, OF LOS ANGELES, CALIFORNIA

DESIGN FOR AN ORNAMENT FOR AUTOMOBILE RADIATOR CAP OR THE LIKE

Application filed March 23, 1931. Serial No. 39,207. Term of patent 3½ years.

To all whom it may concern:

Be it known that I, DORA FOLEY, a citizen of the United States, residing at Los Angeles, in the county of Los Angeles and State of California, have invented a new, original, and ornamental Design for an Ornament for Automobile Radiator Cap, or the like, of which the following is a specification, reference being had to the accompanying drawings, forming a part thereof:

Fig. 1 is a side elevation of an ornament for automobile radiator cap or the like, showing my new design; and Fig. 2 is a front elevation of the same.

I claim:

The ornamental design for an ornament for automobile radiator cap, or the like, as shown.

DORA FOLEY.
